UNITED STATES PATENT OFFICE.

LEWIS B. WHITE, OF NEW YORK, N. Y., ASSIGNOR TO LEON ABBETT, OF JERSEY CITY, NEW JERSEY.

CABLE-GRIP.

SPECIFICATION forming part of Letters Patent No. 350,028, dated September 28, 1886.

Application filed October 20, 1885. Serial No. 180,421. (No model.)

To all whom it may concern:

Be it known that I, LEWIS B. WHITE, a citizen of the United States, residing at New York, in the county and State of New York, have invented a new and useful Improvement 5 in Cable - Grips, of which the following is a specification.

The object of my invention is to provide a new and improved cable-grip which is simple 10 in construction, grips and releases the cable rapidly, and holds it firmly and securely.

The invention consists in the construction and combination of parts and details, and will be fully described and set forth hereinafter, 15 and then pointed out in the claims, reference being had to the accompanying drawings, in which—

Figure 1 is a longitudinal partially-sectional view of my improved grip. Fig. 2 is a side 20 view of the same, partly in section on line x'x of Fig. 1. Fig. 3 is an inverted sectional plan view of the same on the line y'y of Fig. 1.

Similar letters refer to similar parts throughout the several views.

25 The cylinder A is held vertically in a strong frame, A', on the under side of the car, and contains the piston B, from which the piston-rod C projects through a stuffing - box in the bottom of the cylinder, and has its lower end 30 connected with a downwardly-projecting rod, D. A frame, E, is arranged in the direction of the length of the car, and is secured to the lower ends of metal plates F, projecting downward from the bottoms of the car. The frame E is 35 adapted to be received in the cable-trough, and is provided on each side with two pairs of gripping-jaws, G G', one pair at each side of the rod D, and all mounted to slide vertically on the sides of the frame E. The upper and lower connecting-bars of the frame E serve to limit the 40 motion of the gripping-jaws G G', and in the central open space of the frame E the rod D on the piston-rod C operates. The upper jaws, G, are connected by the connecting - rods H 45 with the T-levers J, pivoted on each side of the plates F, and the lower jaws, G', are connected by the connecting-rods I with the opposite ends of the T-levers J. The shanks of the levers J are connected by the rods K with 50 the levers L, pivoted on the plates F, and having their adjacent swinging ends L' forked to

receive between them the sleeve M, mounted rigidly on the lower end of the piston-rod C, and provided with the top and bottom collars, d and g, the fastening-key being passed through 55 the collar d and piston-rod C. From the sides of the lower end of the bar D the forked arms O project upward and outward, and in the forks of the arms O the rollers P are journaled, which run on the sides of the cable-trough, (not shown,) thus serving as guides for the grip. Wedge - shaped lugs Q project from the sides of bar D, a short distance above the lower end of the same, and the outer edges of the lugs are inclined inward and downward, 60 as shown in Fig. 2. Rollers R are journaled on the sides of the frame E, and serve to support the cables freely when not gripped, said cables being shown at V, one at each side of the frame E. The pipes S and T conduct 65 compressed air into the upper and lower ends of the cylinder A, and are provided with the four-way cock W, or with any other suitable regulating device.

The operation is as follows: When the operating-cables V rest on the rollers R, as 70 shown in Fig. 1, and the same are to be gripped to propel the car, compressed air is admitted into the lower end of the cylinder A, the piston B is forced upward, and near 75 the end of its movement the collar g on the sleeve M strikes the forked ends of the lever L, thereby, through the connecting rods and levers, pressing the gripping-jaws G G' firmly on the cables, which are thus firmly gripped. 80 To release the cables, the compressed air is permitted to escape from the lower end of the cylinder, allowing the piston to descend, and the levers L, being no longer supported, fall 85 of their own weight and that of their connections to their former positions, thus separating the jaws G G'. If it is desired to throw the cables entirely off the grip, compressed air is admitted into the upper part of the cylinder A, whereby the bar D is forced downward, 90 causing the beveled lugs Q to press the cables out from the frame E off the rollers R, and thus permitting the cables to drop past the lower jaws, G', into their normal positions above the projecting arms O. When the 95 cables are to be taken up again, compressed air is admitted into the lower part of the cyl-

inder, and the bar D raised, thereby lifting the cables resting on the arms O past the rounded outer surfaces of the lower jaws, G', until they slip upon the rollers R and over the lower jaws. The cables can then be gripped, as before described. It will be observed that the piston-rod can move up and down to take up or throw off the cables without the collar g striking the levers L to grip the same. The rod D is made flexible, so that it can yield on either side in case any obstructions are struck by the same in the cable-trough.

Having thus described my invention, what I claim as new, and desire to secure by Letters Patent, is—

15. In a cable-grip, the combination, with a plate, of two pairs of gripping-jaws on each side of the same, substantially as herein shown and described.
20. 2. In a cable-grip, the combination, with a plate, of a pair of gripping-jaws mounted to slide vertically on said plate, and of a compressed-air cylinder, a piston in the same, and a piston-rod connected by rods with the jaws, substantially as herein shown and described.
25. 3. In a cable-grip, the combination, with a compressed-air cylinder, a piston in the same, and a piston-rod connected with the piston, of a rod projecting down from the piston-rod and 30 provided with lateral projections at its lower end, and of cable-gripping jaws operated from the piston-rod, substantially as herein shown and described.
35. 4. In a cable-grip, the combination, with the vertically-moving rod C, of the rod D, projecting down from the same, which rod D is provided on its lower end with two lateral 40 projections on the same side, the cable being between the said projections, substantially as herein shown and described.
45. 5. In a cable-grip, the combination, with the vertically-moving rod C and mechanism for operating the same, of the rod D, projecting downward from the piston-rod C, the arms O, and the beveled lugs Q on the side of the said rod, and of cable-gripping jaws operated from the said vertically-moving rod C, substantially as herein shown and described.
50. 6. The combination, with a cable-grip rod, of arms on the lower end of the same, which arms project from the side of the rod and upward and outward, substantially as herein shown and described.
7. In a cable-grip, the combination, with a

frame to be fastened on the under side of the 55 car, of sliding grip-jaws on the bottom part of the said frame, the T-shaped levers J, pivoted on the frame and connected by suitable rods with the jaws, the pivoted levers L, connected with the T-shaped levers J, the rod C, which 60 operates the levers L, the piston B, and cylinder A, substantially as herein shown and described.

8. In a cable-grip, the combination, with the cylinder A, the piston B, and the piston-rod C, of the flanged sleeve M on the piston-rod, the pivoted levers L, acted upon by the flanges of the sleeve M, and gripping-jaws operated from the levers L, substantially as herein shown and described.

9. In a cable-grip, the combination, with the cylinder A, the piston B, and the piston-rod C, of the levers L, operated from the piston-rod C, gripping-jaws operated from the levers L by means of suitable rods, the rod D, 75 projecting down from the piston-rod C, the bevel lugs Q, and the inclined arms O on the lower end of the said rod D, and of a frame on which the gripping-jaws slide, substantially as herein shown and described.

10. In a cable-grip, the combination, with two jaws mounted to move toward and from each other, of a frame on which they are mounted, a T-shaped lever having the opposite ends connected with the two jaws, and of mechanism for operating the T-shaped lever, substantially as herein shown and described.

11. In a cable-grip, the combination, with a cylinder and a piston in the same, of tubes for conducting compressed air into both ends 90 of the cylinder, cable-gripping devices, and levers for operating said gripping-devices from the piston in the cylinder, substantially as herein shown and described.

12. In a cable-grip, the combination, with 95 a cylinder, a piston in the same, and a piston-rod projecting from the piston, of a cable-lifting device on the piston-rod, substantially as shown and described.

13. In a cable-grip, the combination, with 100 a cylinder, a piston in the same, and a piston-rod projecting from the piston, of an inclined plane projecting on an extension of the piston-rod, substantially as shown and described.
